WRENCH

Vincent Bernesser, Shandaken, N. Y.

Application February 6, 1936, Serial No. 62,564

1 Claim. (Cl. 81—3.1)

My invention relates to screw wrenches.

The object of my invention is to provide an efficient wrench by means of which jar tops of the screw type may be easily and quickly opened or securely closed.

A further object is to provide a construction that may be made at a very low cost by stamping and pressing operations, and that will be light in weight.

10 All of the parts may be made of sheet metal.

Referring to the drawings which form a part of the specifications;

Fig. 1 is a perspective view of a jar having a screw cap or top thereon, and a wrench embodying my invention affixed to the cap in position to rotate the cap in either direction required to tighten or loosen it on the jar.

Fig. 2 is an inverted plan view of the wrench, the sleeve portion of the handle being shown in 20 longitudinal section.

Fig. 3 is a cross sectional view taken on line 3—3 of Figure 2, showing the sleeve and shank portion of the handle in operative engagement.

Fig. 4 is a cross sectional view showing the 25 sleeve and shank portions of the handle in disengaged relation.

10 indicates a fruit jar, and 11 the usual screw cap or top thereof.

In Figure 2, the broken circles illustrate caps of 30 different diameters, showing the wrench in position to engage a top having either a small or large diameter.

12 indicates the bar formed from a sheet of 35 mild steel or other suitable material, and with the V-shaped jaw member formed integral therewith, its upper side 12' lying in a plane with the flat side of the bar 12, and having an end wall 15 which carries a V-shaped flange 16 which extends inwardly and is spaced from the upper side 40 12' a predetermined distance, as illustrated.

The inner edge of the flange 16 is preferably formed with teeth 17 as shown, arranged in a row on one or both sides of the V-shaped edges.

13 indicates the sleeve portion of the handle, 45 and 14 a sliding jaw portion.

The tubular sleeve is formed with threaded portions 18—18 respectively, located on opposite sides as shown, which engage with the threaded parts 19—19 respectively, formed in the shank 50 of the bar 12.

The jaw member 14 is free to slide on the bar, and is formed with teeth 14' carried on an offset portion 14² as shown.

It will now be understood that the teeth are required on either one side of the V-shaped jaw 5 or on the sliding member 14, to prevent the wrench from slipping on the cap in the act of opening the jar, but I prefer to have them formed in all three of the edges mentioned, as shown in the drawing.

20 indicates a hook formed integral with the bar and located near the apex of the V, and is used to remove caps of the anchor type.

When the sleeve 13 is in the position relative to the bar as illustrated in Figure 4, the sleeve 15 may freely slide on the bar until the sleeve is rotated to cause the threads to engage the threads of the bar, and thereafter, on rotating the sleeve, the member 14 is forced into locking engagement with the cap, as will be readily understood.

The construction as shown provides three sets of teeth, each set arranged in a straight row, each row extending at an angle to the other two rows, making an effective wrench.

Having thus described my invention I claim 25 as new:

A wrench of the character described consisting of three pieces, one of which comprises a flat bar portion having threads formed in its side edges only, and having a V-shaped head formed 30 on one end, said head being of substantially channel formation in cross-section defining upper and lower parallel walls continuing through the bight of the V-shaped head, and an outer end wall, 35 the upper wall being integral with the flat bar portion and the lower wall having its free edge presented for engagement with a jar cap with the uninterrupted intermediate portion of the lower wall acting to strengthen the end portions of 40 the lower wall when the wrench is in service, a tubular handle portion having discontinuous threads formed therein adapted to engage with the threads on the bar in one position and to be disengaged therewith when in another position, 45 and a jaw member carried on the bar in slidable relation between the inner end of the handle and the V-shaped head.
